CARD PUNCHING MACHINE

Philippe Pol Charbonneaux, Paris, France, assignor to
Societe Industrielle Bull-General Electric (Societe
Anonyme), Paris, France

Filed Mar. 15, 1965, Ser. No. 84,262

Claims priority, application France Oct. 13, 1964

Term of patent 14 years

(Cl. D26—5)

FIG.1

FIG.2

FIG.3

FIG.4

FIG.5

FIG.6

FIG.7

FIG.8

FIGURE 1 is a perspective view from the front, top and left side of a card punching machine embodying my new design;

FIGURE 2 is a right side elevational view thereof;

FIGURE 3 is a top plan view thereof; and

FIGURE 4 is a rear elevational view thereof.

FIGURE 5 is a perspective view from the front, top and left side of the machine of FIGURE 1, showing a modified embodiment thereof;

FIGURE 6 is a left side elevational view thereof;

FIGURE 7 is a top plan view thereof; and

FIGURE 8 is a rear elevational view thereof.

The right side of the modified embodiment shown in FIGURES 5-8 is the same as the right side shown in FIGURE 2.

I claim:

The ornamental design for a card punching machine, substantially as shown and described.
